UNITED STATES PATENT OFFICE.

JOHN SPENCER WALKER, OF TRENTON, NEW JERSEY.

DESIGN FOR A TOWEL-HOLDER.

SPECIFICATION forming part of Design No. 34,492, dated May 7, 1901.

Application filed March 9, 1901. Serial No. 50,526. Term of patent 3½ years.

To all whom it may concern:

Be it known that I, JOHN SPENCER WALKER, a citizen of the United States, residing at Trenton, in the county of Mercer and State of New Jersey, have invented a certain new and useful Design for a Towel-Holder; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to a design for a towel-holder, of which the following is a specification, reference being had to the accompanying drawings, forming a part thereof.

In the accompanying drawings, Figure 1 is a perspective view of the towel-holder. Fig. 2 is a central longitudinal sectional view. Fig. 3 is a top end view, and Fig. 4 is a bottom end view.

As shown in the drawings, the design con-

sists of a hollow receptacle A, having an octagonal outlined circumference, and at one end of the holder project two rectangular outlined portions B, which are spaced apart. The opposite end of the holder has flat tapering faces C, which terminate in the marginal edge of a central aperture through the wall of the holder. In the circumference of the holder is a circular outlined aperture D, which merges into an elongated slot E, which extends to the central aperture in the bottom of the holder.

35

Having thus described my invention, what I claim is—

The design for a towel-holder as herein shown and described.

In testimony whereof I hereunto affix my signature in presence of two witnesses.

JOHN SPENCER WALKER.
